UNITED STATES PATENT OFFICE.

CHARLES A. CHASE, OF CHICAGO, ILLINOIS.

ELECTRIC RECEPTACLE.

No. 832,718.

Specification of Letters Patent.

Patented Oct. 9, 1906.

Application filed April 29, 1905. Serial No. 258,000.

To all whom it may concern:

Be it known that I, CHARLES A. CHASE, a citizen of the United States, residing at Chicago, in the county of Cook and State of Illinois, have invented certain new and useful Improvements in Electric Receptacles; and I do hereby declare the following to be a full, clear, and exact description of the invention, such as will enable others skilled in the art to which it appertains to make and use the same.

My invention relates to receptacles for incandescent electric lamps; and it consists in a new construction of receptacles particularly adapted to be used in electric signs which is neat, compact, strong, simple, economical to manufacture, and adapted to be easily and firmly secured in position and easily removed, if desired.

20 A desirable form of my receptacle is shown in the drawings herewith, in which the reference-numerals of the specification indicate the corresponding parts in all the figures.

Figure I is a vertical section. Fig. II is a top plan. Fig. III is a rear plan. Fig. IV is a section of the top or rear portion of the receptacle at a right angle to Fig. I.

In the figures, 1 indicates the body or base, of porcelain or other suitable insulating material, preferably circular and having a socket on its lower "face," so-called, preferably surrounded by a short annular flange 2, within which is arranged the central-lamp terminal 3 and the outer-lamp terminal 4 in the form 35 of an outwardly-extending threaded shell, preferably of brass or copper. On the upper or rear surface of the base are the recesses—one straight, 5, and the other curved or marginal, 6—by which the wire-terminals 7 and 40 8, correspondingly formed, are positively separated and maintained securely in position. An integral margin 9 surrounds said recesses containing the wire-terminals, preferably having its outer edge beveled and 45 formed with opposite notches 10 for the outwardly-extending ends of the wire-terminals and with holes to receive the tips of the binding-screws 11. The space within the margin may be filled with insulating-cement 12.

50 The central-lamp terminal may be in the form of a split washer secured in place by screw 13, which also secures in place the straight terminal 7 and makes connection therewith. The threaded shell is secured by 55 securing-screws 14, one or both of which may engage with curved-wire terminal 8 to make

connection therewith and secure that also on the brace. 15 is a washer which may be set against the flange of lamp-terminal 4. To this threaded shell is fitted a threaded ring 60 16, of porcelain or other insulating material, and preferably of similar diameter to the base, which may have a knurled outer edge, rendering manipulation easier, and an inner annular rabbet 17 to receive the flange 2 65 when the supporting-board or face-plate is very thin. As here shown, the face-plate 18 is supposed to be of rather thin sheet metal, and the receptacle is quickly and firmly secured thereon by the ring, so that only the 70 slightly ring is seen on the front of the sign. The holes in the face-plate may be about large enough to receive the flange on the base.

It will be seen that the receptacle is 75 clamped to the supporting-body, such body being held against the relatively broad bearing-surface formed on the back section or base-section 1 outside of the flange 2 by the front section or ring 16. The flange 2 is interposed between the metal socket 4 and the supporting-body, which will ordinarily be of metal. These two metallic bodies are therefore effectively insulated. The rabbet 17 in the front section or ring 16 permits the use of 80 supporting bodies or plates of various thickness. The flange 2 extends into the rabbet and makes a complete insulation. The use of the external threading on the socket common to receptacles for Edison lamps for the 85 purpose of clamping the two sections together and securing the receptacle to the supporting-body has the great advantage of simplicity and economy of construction.

Having thus described my invention, what 90 I claim as new, and desire to secure by Letters Patent, is—

1. In a receptacle for electric signs, the combination with a circular porcelain base of a substantially uniform diameter and having 100 a circular margin on its back, a curved marginal recess and a straight central recess formed within said margin, and a socket or recess on its face, a marginal-wire terminal and a central-wire terminal fitted to the respective recesses and having tips extending 105 outwardly and oppositely in notches in said margin, binding-screws in said tips having their ends received in holes in the porcelain lamp-terminals arranged on the face of the 110 body, a screw connecting the central-lamp terminal to the central-wire terminal and se-

curing said central terminal in position, a screw connecting the outer or marginal-lamp terminal to the marginal-wire terminal and securing said terminals in position, and 5 means to secure the receptacle on a sign-plate.

2. A relatively thin supporting-body having a perforation in combination with a lamp-receptacle comprising a back section of insulating material lying against one side of the supporting-body, an externally and internally screw-threaded socket secured to the back section so as to extend through the perforation in the supporting-body, and a front 15 section of insulating material having an internal thread so as to screw onto the end of the socket and against such supporting-body.

3. A relatively thin supporting-body having a perforation, in combination with a lamp-receptacle comprising a back section of insulating material having a flat bearing part lying against one side of the supporting-body, an externally and internally screw-threaded socket secured to the back section so as to 20 extend through the perforation in the supporting-body, and a front section of insulating material having an internal thread so as to screw onto the end of the socket and against the portion of the supporting-body 25 in contact with the flat bearing-surface of the back section.

4. A relatively thin supporting-body having a perforation, in combination with a lamp-receptacle comprising a back section of insulating material lying against one side of the supporting-body, an externally and internally screw-threaded socket secured to the 30 back section so as to extend through the per-

foration in such supporting-body, a flange on the back section lying between the socket 40 and the material of the supporting-body, and a front section of insulating material having an internal thread so as to screw onto the end of the socket and against such supporting-body.

5. A relatively thin supporting-body having a perforation, in combination with a lamp-receptacle comprising a back section of insulating material lying against one side of the supporting-body, an externally and internally screw-threaded socket secured to the back section so as to extend through the perforation in such supporting-body, a flange on the back section lying between the socket and the material of the supporting-body, a front 55 section of insulating material having an internal thread so as to screw onto the end of the socket and against such supporting-body, and a rabbet on the front section to receive the flange on the back section.

6. In a receptacle for incandescent lamps, the combination of a base of porcelain, with a circular socket forming one lamp-terminal on the front side of said base, a lamp-terminal arranged centrally in said socket, a pair of 65 terminals for the circuit-wires lying in channels formed in the back of said porcelain base, and connections between said terminals and the lamp-terminals in the front side of the base.

In testimony whereof I affix my signature in presence of two witnesses.

CHARLES A. CHASE.
